UNITED STATES PATENT OFFICE.

GLENN D. ANGLE AND GEORGE E. A. HALLETT, OF DAYTON, OHIO.

ENGINE CYLINDER.

Application filed December 30, 1920. Serial No. 434,136.

This invention relates to the cylinders of internal combustion engines and relates particularly to a type of joint to be used for the purpose of holding a cast aluminum cylinder head to a steel cylinder barrel. The purpose of this joint is to lock the aluminum head securely to the steel barrel in such a manner as to prevent expansion both laterally and longitudinally when the aluminum, which has a higher co-efficient of expansion than the steel, becomes heated.

With the above and other objects in view the invention consists in the novel construction, combination and arrangement herein fully described as well as the method of forming the joint between the cylinder barrel and cylinder head, the same being fully set forth in the specification, illustrated in the drawings, and claimed.

Figure 1 is a diagrammatic section through a cylinder and cylinder head illustrating the present invention;

Figure 2 is a plan view of the head showing some of the formation thereof in dotted lines;

Figure 3 is an enlarged fragmentary longitudinal section through the cylinder; and

Figure 4 is a detail plan view of a fragment of the cylinder barrel.

Referring to the drawings, 10 designates the barrel of the cylinder which is ordinarily formed of steel of any suitable wall thickness. In carrying out the present invention, and in order to enable an aluminum cylinder head to be cast thereon and around the same, that end of the barrel which lies contiguous to the cylinder head is formed with one or more peripheral ribs 11 of dove-tail shape in cross section, and is further formed with one or more annular recesses 12 also of dove-tail shape in cross section. In addition to the parts 11 and 12, just referred to, the cylinder wall is formed with a circumferential flange 13 which lies at the base of the completed cylinder head and is also formed with a peripheral projecting flange 14 which is shaped like a hook in cross section, a part of said hook-shaped flange forming two of the walls of the dove-tailed groove or channel 12, above referred to. Furthermore the cylinder walls are formed between the flanges

13 and 14 with additional grooves 15 and 16, each of which is of dove-tailed formation in cross section.

When the aluminum cylinder head, indicated at 17, is cast around the adjacent end of the cylinder barrel, the molten metal flows into and fills the several grooves described in connection with the adjacent end of the cylinder wall or barrel 10, thereby forming an interlocked connection and thermal bond between the cylinder barrel and the cylinder head. The arrangement of the dove-tailed grooves and ribs is such as to prevent undue expansion and contraction, either longitudinally or transversely of the barrel and cylinder head so that the more the cast aluminum cylinder head expands the tighter will the inclined surfaces or walls of said grooves and ribs bind against each other.

It is claimed that the joint herein fully described and shown will remain intact while under the influence of extreme heat and sufficiently locked to withstand the forces of explosion within the combustion chamber of an internal combustion engine. In view of the fact that the grooves are wider at the bottom than at the top any expansion in a direction away from the cylinder barrel draws the aluminum against the tapered or inclined surfaces and insures a tight joint. To overcome the difficulty of completely filling the grooves in the barrel with the aluminum, slots or recesses 18 are formed in the end of the barrel so as to intersect the annular grooves, thereby permitting a free flow of the molten aluminum to the grooves so as to completely fill the latter. The joint referred to has been found particularly effective in the connection noted where the greater expansion of the aluminum tends to permit the metal to pull away from the steel under conditions of extreme heat, thus destroying the thermal bond. When such pulling away occurs a film of oil is apt to creep in between the aluminum and steel destroying the thermal bond and militating against the flow or carrying off of the heat of the cylinder wall.

What we claim as new is:

1. The method of fastening a cylinder head to a cylinder barrel, the same consist-

ing in forming the barrel with a plurality of annular grooves the opposite walls of which are undercut and reversely inclined from the bottom to the top forming a groove 5 in the end of said cylinder barrel, the opposite walls of which are undercut and reversely inclined from the bottom to the top providing at intervals recesses intersecting said grooves, then casting the cylinder head 10 around the adjacent end of the barrel so that portions of the material of the cylinder head will run along and fill said grooves.

2. In combination, a cylinder barrel, an annular dove-tailed groove extending around said barrel, the upper horizontal 15 surface of said barrel provided with an annular dove-tailed groove, and an aluminum cylinder head cast around said barrel having portions thereof fitting said grooves.

In testimony whereof we have affixed our 20 signatures:

GLENN D. ANGLE,
GEO. E. A. HALLETT.
